2,438,149

STOPPER

Fred A. Cutter, Berkeley, and William F. Butler, Oakland, Calif., assignors to Cutter Laboratories, Berkeley, Calif., a corporation of California

Application December 18, 1945, Serial No. 635,840

2 Claims. (Cl. 215—47)

1

This invention relates to stoppers for flasks used for shipping, retaining and making intravenous injections.

All interior surfaces of flasks and stoppers used for administering intravenous injections must be absolutely sterile and free of all foreign matter which might in any way react with the contents of the flask. During recent years we have found that, although biologic solutions, such as glucose and saline solutions, are crystal clear when bottled, upon standing they become contaminated with a precipitate. The reasons for this have been found to be twofold. In the first place, although the quality of glass is constantly being improved it is still not entirely inert to some biologic solutions. In the second place, the only stoppers available have been made of rubber containing a filler which, upon standing in contact with biologic solutions, is leached out and produces a precipitate. Although in some cases the quantity of precipitate is extremely small and results in no injury to the patient, the Pure Food and Drug Commission, nevertheless, requires that such solutions be crystal clear.

In an attempt to avoid the formation of such precipitates, the stoppers have been thoroughly washed in both acid and alkaline solutions but, in spite of this, precipitates still form. Another expedient resorted to in an attempt to overcome this problem was to coat the exposed surface of the stopper with material inert to the solutions in question. This coating was applied by passing the stoppers through a plurality of opposed pairs of sprays and rotating the stoppers during their passage through the sprays. However, stoppers used for this purpose are provided on their lower ends with one or more upwardly extending, straight walled, circular recesses through which access is had to the interior of the flasks. It was found that because of these recesses, it was impossible effectively to coat the stoppers, regardless of the number of sprays used and regardless of the fact that they were rotated during their passage between the sprays. Furthermore, these recesses, which are relatively deep, made it impossible thoroughly to wash the stoppers prior to applying them to their flasks.

Access through this type of stopper is had by passing a hypodermic needle therethrough, the needle being connected through a suitable tubing and a hypodermic needle on its free end with the patient. This method of gaining access to the interior of the flask has the advantage that if the depth of the stopper through which the needle passes is sufficiently long, the incision made by

2

the hypodermic needle is automatically sealed when the needle is withdrawn. It has been found, however, that when a hypodermic needle is injected through a stopper in a direction substantially transverse to the face thereof, a small core, having a depth substantially equal to the internal diameter of the needle, is cut from the stopper and either blocks the stopper or restricts the flow of the liquid therethrough.

10 Flasks and stoppers of the character under discussion are frequently used for receiving blood from a donor and for subsequently administering such blood to a patient. When used for this purpose, the flask is provided with a small quantity of a blood non-coagulant such as sodium citrate. Although the sodium citrate decreases the formation of blood clots, it does not altogether prevent it and, on occasions, these clots, due to the construction of the stopper and method of making the discharge connection therewith, restrict or block the flow of blood from the flask.

One of the objects of this invention is the provision of a stopper formed on its inner surface with an outwardly diverging recess capable of being effectively coated with an inner coating, into which the inner end of a glass nipple may be inserted and which serves as a sump surrounding the end of the nipple for the reception of any blood clots which may settle on to the inner end 30 of the stopper when the flask is in an inverted position.

A further object of the invention is the provision in a stopper of the character described of an elongated hypodermic needle entrance recess disposed over an inclined portion of the lower end of the stopper so that an attendant can selectively insert the hypodermic needle through a portion of the stopper of predetermined and variable thickness.

40 The invention possesses other advantageous features, some of which with the foregoing will be set forth at length in the following description where that form of the invention which has been selected for illustration in the drawings accompanying and forming a part of the present specification is outlined in full. In said drawings, one form of the invention has been illustrated, but it is to be understood that it is not limited to such form, since the invention as set forth in the 50 claims may be embodied in a plurality of other forms.

Referring to the drawings:

Figure 1 is a vertical midsection taken through an inverted flask and its stopper in which the 55 objects of our invention have been embodied.

Figure 2 is a section taken on the line 2—2 of Figure 1 showing the inverted stopper in bottom plan view.

As shown in these figures, the objects of our invention have been embodied in a stopper 1, provided on its outer end with an outwardly extending flange 2, arranged to seat on the outer end of the neck 3 of a flask 4. Formed on the inner end of the stopper is an outwardly diverging recess 5, defined by a generally vertical wall 6, merging at its lower end with an upwardly inclined wall 7. The outer end of the stopper is formed with an inwardly extending recess 8 in registration with the innermost portion of the recess 5 and which is separated from the latter recess by a relatively thin diaphragm 9. The diaphragm 9 is of such thickness that it can be readily ruptured by a hypodermic needle to receive and permit the passage of the tapered end 11 of a glass nipple 12, the free outer end of the nipple being connected with a suitable rubber tube or a hose 13.

Also extending into the stopper from its inner face is a circular opening 14 for the force-fit reception of an air-eduction tube 15.

Sprayed over the entire inner surface of the stopper 1, including the inwardly divergent recess 5, is a film or coating 16 of any suitable material inert to the biologic solutions contained in the flask, there being many such materials available on the open market for this purpose.

Extending downwardly from the outer face of the stopper is an elongated, slightly arcuate hypodermic needle entrance recess 17, the bottom of which is V-shaped in cross-section, as shown in Figure 1. By inserting a hypodermic needle into the recess 17 and injecting the needle through the stopper at this zone, the formation of a core is obviated due to the inclined inner V-shaped walls of the recess 17. From Figure 1, it is to be noted that the recess 17 is in vertical alignment with the inclined wall 7 of the recess 5, and from Figure 2, it will be noted that the depth of material through the stopper increases from point A to point B, and from point B to point C. The effectiveness with which an incision made through a stopper is automatically sealed when the hypodermic needle is withdrawn depends upon the depth of material through which the needle penetrates. Since for this reason some medical branches of the armed services require a greater depth of material at this point than do other branches, it has been necessary in the past to provide the armed services with stoppers made in accordance with various specifications. However, by resorting to the expedient above described, a standard stopper can be made to comply with all of the specifications in question for the doctor or attendant to select the depth of material through which the needle is made to pass. Conveniently the points A, B and C can be designated in terms of the actual number of

millimeters through which the needle passes at these points.

In line with the tube 15 on the outer face of the stopper is a small indentation or recess 18 serving to locate that point on the outer face of the stopper through which a hypodermic needle must be inserted in order to penetrate into the tube 15 for establishing communication between the interior of the flask 4 and atmosphere.

From the above description, it will be noted that: The outwardly divergent recess 5 permits the entire exposed lower portion of the stopper effectively to be coated with a protective film inert to the contents of the flask and that this recess defines a sump for the reception of any blood clots which may settle to the inner end of the stopper. The arcuate inwardly convergent recess 17 avoids the formation of any core when a hypodermic needle is injected through the stopper at any point along this zone and, due to the fact that the depth of the stopper varies along the length of the recess 17, an operator or attendant can select the depth of the stopper through which he desires to pass the hypodermic needle so as to comply with the varying regulations of the different medical units.

We claim:

1. A stopper designed for use in conjunction with a flask for making intravenous injections, the upper surface of said stopper being formed with a transversely elongated and downwardly converging hypodermic needle entrance channel and said stopper being of varying depth at points along said channel.

2. A stopper for use in conjunction with a flask for making intravenous injections, the inner end of said stopper being formed with an outwardly diverging recess arranged to receive and accommodate the inner end of a connecting nipple, and which serves as a sump immediately adjacent the inner end of said nipple for the reception of solid matter when the stopper is in an inverted position, the outer end of said stopper being formed with a transversely elongated and downwardly converging hypodermic needle entrance channel overlying said recess, and wherein the depth of said stopper varies along said channel.
